UNITED STATES PATENT OFFICE.

JOHN HAYES, OF AMSTERDAM, NEW YORK, ASSIGNOR TO UNION SPECIAL MACHINE COMPANY, OF CHICAGO, ILLINOIS, A CORPORATION OF ILLINOIS.

SEWING-MACHINE.

1,080,967.

Specification of Letters Patent.

Patented Dec. 9, 1913.

Application filed November 16, 1911. Serial No. 660,579.

To all whom it may concern:

Be it known that I, JOHN HAYES, a citizen of the United States, residing at Amsterdam, in the county of Montgomery, State of New York, have invented certain new and useful Improvements in Sewing-Machines, of which the following is a description, reference being had to the accompanying drawings and to the letters and figures of reference marked thereon.

The invention relates to new and useful improvements in sewing machines, and has for an object to provide a fabric-guiding device which may be moved away from and toward the stitching mechanism, together with devices for moving the fabric-guiding device, which devices include means for raising the presser foot.

A further object of the invention is to provide devices of the above character which may also be operated to release the tension on the thread, so that the operator by the movement of a single lever may raise the presser foot, release the tension on the thread and withdraw the fabric-guiding device from the stitching mechanism.

These and other objects will in part be obvious and will in part be hereinafter more fully described.

In the drawings which show by way of illustration one embodiment of the invention, Figure 1 is a front view of a machine having the invention applied thereto; Fig. 2 is a rear view of the same; Fig. 3 is a horizontal sectional view through the standard, showing the work support in plan; Fig. 4 is a detail perspective view, showing the combined mechanism for moving the guide, raising the presser foot and releasing the tensions; Fig. 5 is a sectional view through the binding guide; Fig. 6 is a detail, showing the tensions and the releasing lever therefor; Fig. 7 is a detail in perspective, showing the lever for moving the binding guide; Fig. 8 is a detail in perspective of the arm for releasing the tensions; and Fig. 9 is a sectional view through the presser foot lifting lever, showing the connection for releasing the tensions.

The sewing machine to which the invention is applied, consists of the bed plate 1 on which is supported an overhanging arm 2. At the forward end of the overhanging arm is a needle bar 3, which is reciprocated by a

needle lever 4. The needle lever 4 is connected with the main shaft of the machine. Said needle bar is provided, as herein shown, with two needles 5, 5. Coöoperating with the needles beneath the work support may be any desired form of looper mechanism.

Mounted on the bed plate 1 is a work support 6 on which the fabric is supported and guided to the stitching mechanism. The fabric is held in engagement with the feed dog of the machine by a presser foot 7, which is carried by a presser bar 8. The presser bar 8 is formed with a projecting pin 9, on which rests a leaf spring 10, which yieldingly holds the presser foot against the fabric on the work support. These parts are of the usual construction, and will not need further description.

In order that the presser foot may be raised from the work support, for the purpose of manipulating the fabric, or for inserting or removing the same, a lever 11 is pivoted at 12 to the overhanging arm, and is provided with a forwardly projecting portion which is adapted to engage the pin 9, carried by the presser bar. This lever is held depressed at its forward end by a spring 13. The lever 11 at its rear end is connected to a chain 14. The needle threads pass through suitable tensions 15 and 16, and through suitable guides of the usual construction, to the needles. In order that these tensions may be released when the presser foot is raised, a tension-releasing lever 17 is provided, which lever is pivoted at 18 to the overhanging arm. This lever carries an arm 19, which is formed with spaced fingers 20 and 21. The outer ends of the fingers 20 and 21 are wedge-shaped, and are so disposed that when the lever 17 is swung about its fulcrum, the wedge-shaped ends of these fingers will enter respectively between the clamping disks of the tensions 15 and 16. The other end of the lever 17 is formed with a projecting lug 22, which is located in the path of a bracket 23, adjustably attached to the presser foot raising lever 11. This lug 22 also extends over the lever 11, and will be effectively housed between the upper bent end of the bracket and the lever proper, so that as the lever is moved up and down the lug 22 will cause the tension-releasing lever to be vibrated.

From the above construction, it will be ap-

parent that on the downward movement of the chain or flexible connection 14, the lever 11 will be swung so as to bring the free end thereof into engagement with the pin 9 for raising the presser bar, and said lever will also swing the tension-releasing lever 17 so as to carry the fingers 20 and 21 between the clamping disks of the tensions 15 and 16, and thereby release all tension on the needle threads. This releasing of the tension on the needle threads at the same time that the presser foot is raised, allows the fabric to be readily removed from the machine.

As herein shown, the machine is provided with a guiding device 24, through which a strip of fabric may be guided and the edges thereof folded. This strip of fabric is preferably guided underneath the main body fabric, and will be stitched to the main body fabric by the stitching mechanism. In order that the main body fabric and the attached strip may be bound, I have provided a binder 25. This binder is mounted on a plate 26, which is free to slide transversely of the line of feed or the line of the seam. A stop 27 is attached to the plate and engages the throat plate of the machine to limit the inward movement of the plate. The binder, as herein shown, is of the type described in the patent to W. E. Dickson, No. 891,605, granted June 23d, 1908. Said binder is formed with a U-shaped passage 28, and with an open receiving mouth 29. Said binder is also tapered at its delivery end so as to invert the binding strip. The construction and operation of this binder is fully set forth in said patent and will not need further description. In order to guide a binding strip to the binder, I have also provided a guiding member 30, which is attached to a bracket 31. These parts are also shown in said patent, and will not need further description.

It is sometimes desirable to move the binder away from the stitching mechanism, as, for example, in turning a corner, or upon the finishing of the garment, so that the binding strip may be cut between the binder and the stitching point, and the cut end of the binding properly turned in for the final finishing of the article. In order that this may be readily accomplished, I have provided a lever 32, which is pivoted at 33 to the upper face of the work support. The other end of the lever 32 is pivoted at 34 to the sliding plate 26, on which the binder is mounted. To aid in guiding the sliding plate, I have formed the same with an extension 35, which carries a pin 36 extending through a slot 37 in the bed plate. I have also provided a stop screw 38, which extends into the bed plate, and when the lever 32 is swung to move the plate 26, said plate strikes against the stop screw 38 and the outward movement of the plate and binder

away from the stitching mechanism is thereby limited. The work support is also formed with an arc-shaped slot 39. Rigidly connected to the lever 32 is a bracket 40, which projects downwardly through the arc-shaped slot 39, and is curved to conform to the same. A spring 41 arranged beneath the work support is connected at one end to the bracket 40, and said spring at its other end is secured to a fixed lug on the under face of the work support. This spring normally moves the lever 32 so as to hold the stop 27 in contact with the throat plate of the machine and the binder, in normal position for guiding the binding strip to the stitching mechanism. A chain or other flexible connection 42 is attached to the other end of the bracket 40, and to a lever 43. This lever 43 is pivoted on a bracket 44 carried by the bed plate 1. Said lever is formed with an outwardly projecting arm 45, which is connected by a chain or other flexible connection 46 to the chain 14.

The chain 14 is connected to a suitable foot treadle or knee shift, which is readily accessible to the operator. This treadle or knee shift is of the usual construction and has not been illustrated in the drawings. Upon the downward movement of the chain 14, the lever 11 will be swung, so as to raise the presser foot and release the tension. This lever 11, as clearly shown in Fig. 2, is so positioned that there is considerable movement of the lever before the pin 9 is engaged to lift the presser foot. This lost motion between the lever 11 and the presser foot is taken advantage of in the present construction, to provide a movement of the binder without raising the presser foot. In other words, when the chain is first pressed downwardly, the lever 45 is at once swung about its fulcrum, which will swing the lever 32, and at once withdraw the binder from the stitching mechanism. The binder through this movement of the lever 45 will be moved a considerable distance before the lever 11 engages the pin 9 to raise the presser foot.

The fingers 20 and 21 of the tension-releasing lever are spaced some distance from the tensions, so that the first movement of the tension-releasing lever is ineffective to release the tensions. Therefore, the binder may be moved a short distance away from the stitching mechanism and returned, if desired, without either the raising of the presser foot or the opening of the tensions. A further movement, however, of the treadle or knee shift, will move the binder still farther away from the stitching mechanism, raise the presser foot and release the tensions. It will be noted that this treadle or knee shift may be manipulated so as to move the binder away from the stitching mechanism during the stitching operation, for the

first movement of the binder does not raise the presser foot so as to render the feed ineffective.

While I have shown the invention as applied to a binder, it is obvious that the same may be applied to guides of other forms, wherever it is desired to move the guide away from the stitching mechanism.

While I have also shown the invention as applied to a two-needle stitching mechanism, and the machine is provided with a separate strip-guiding member, it will be obvious that the invention may be applied to other types of sewing machines, and that the strip guide may be entirely omitted.

Having thus described my invention, what I claim as new and desire to secure by Letters Patent, is:—

1. The combination of a binder, stitching mechanism, a presser foot, and means common to the binder and presser foot for moving the binder away from the stitching mechanism and for raising the presser foot.

2. The combination of a binder, stitching mechanism, a presser foot, and means common to the binder and the presser foot for moving the binder away from the stitching mechanism and for raising the presser foot, said means being constructed so that the binder may be withdrawn a short distance from the stitching mechanism before the presser bar is raised.

3. The combination of a binder, stitching mechanism, a presser foot, means for moving the binder in a transverse direction with respect to the line of seam at the will of the operator during the stitching operation, said means including devices for raising the presser foot after the movement of the binder has taken place.

4. The combination of a binder, stitching mechanism, a presser foot, means for moving the binder in a transverse direction with respect to the line of seam at the will of the operator during the stitching operation, said means including devices for raising the presser foot, and devices for releasing the tensions on the needle threads.

5. The combination of a binder, stitching mechanism, a lever for withdrawing the binder from the stitching mechanism, a lever for raising the presser foot, and means for simultaneously swinging said levers.

6. The combination of a binder, stitching mechanism, presser foot and tension release, manually-operated means common to the binder, presser foot and tension release for moving the binder, presser foot and tension release in one direction, and automatic means for returning the devices to normal position.

7. The combination of a binder, stitching mechanism, a presser foot, means for moving the binder in a transverse direction with respect to the line of seam at the will of the

operator during the stitching operation, said means including devices for raising the presser foot, devices for releasing the tensions on the needle threads, and means for automatically returning the parts to normal position.

8. The combination of a binder, stitching mechanism, presser foot and tension-releasing device, and means common to the binder, presser foot, and tension release for moving the binder away from the stitching mechanism, for raising the presser foot, and for operating the tension release.

9. The combination of a binder, stitching mechanism, a presser foot, a lever for moving the binder in a transverse direction with respect to the line of seam, a lever for raising the presser foot, a tension-releasing lever, and means for simultaneously swinging all of said levers.

10. The combination of a binder, stitching mechanism, a presser foot, a lever for moving the binder in a transverse direction with respect to the line of seam, a spring for holding the binder in normal position adjacent the stitching mechanism, a lever for raising the presser foot, and common means for swinging the lever for moving the binder and for swinging the lever for raising the presser foot.

11. The combination of a binder, stitching mechanism, a presser foot, a lever for moving the binder in a transverse direction with respect to the line of seam, a spring for holding the binder in normal position adjacent the stitching mechanism, a lever for raising the presser foot, common means for swinging the lever for moving the binder and for swinging the lever for raising the presser foot, and a tension-releasing lever operated by the presser foot raising lever.

12. The combination of a work support, stitch-forming mechanism including a needle, a binder, a plate slidably mounted on said work support, a lever attached to said plate, a spring engaging said lever for moving said plate toward the stitching mechanism, a stop for limiting the inward movement of the plate, means for engaging said lever for moving the plate to withdraw the binder from the needle, and a stop for limiting the outward movement of the plate.

13. The combination of a work support, stitch-forming mechanism including a needle, a binder, a plate slidably mounted on said work support, a lever attached to said plate, a spring engaging said lever for moving said plate toward the stitching mechanism, a stop for limiting the inward movement of the plate, means for engaging said lever for moving the plate to withdraw the binder from the needle, and a stop for limiting the outward movement of the plate, said plate having an outwardly projecting extension, and a pin carried thereby and en-

gaging a slot in the work support for guiding the plate.

14. The combination of a work support, a plate slidably mounted thereon, a binder carried by said plate, a lever engaging said plate for moving the same, a spring for moving the lever in one direction, a second lever having a flexible connection with the first lever for moving the same, and a flexible connection for said second lever, whereby the same may be moved during the stitching operation, a presser foot, a lever for rais-

ing the presser foot, a tension device, a releasing lever for the tension device, operated by the presser foot raising lever and a flexible connection between the presser foot raising lever and the flexible connection for said second lever. 15

In testimony whereof I affix my signature, in presence of two witnesses.

JOHN HAYES.
